(57) CLAIM

The ornamental design for a play yard, as shown and described.

DESCRIPTION

FIG. 1 is a perspective view of a play yard, showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a perspective view showing the play yard within an environment of use.

The broken lines depict some portions of the play yard or environmental subject matter and form no part of the claimed design.

1 Claim, 5 Drawing Sheets
